SPHERICAL TANK FOR STORAGE VACUUM SERVICE OR SIMILAR USE

Christian Arne, Chicago, Ill., assignor to Chicago Bridge
& Iron Company, Chicago, Ill., a corporation of Illinois

Filed Sept. 26, 1961, Ser. No. 66,859

Term of patent 14 years

(Cl. D91—1)

FIGURE 2 is an elevation view of FIG. 1 looking at FIG. 1 from a position facing what appears to be the bottom of the drawing, the opposite side being substantially the appearance, except for the uniformly spaced median horizontal ribs, indicated in FIGS. 1 and 3, and excepting the fact that the elongated median rib member on the front of FIG. 2 is absent in the rear view as shown by FIG. 3.

FIG. 3 is a view of the structure of FIG. 1 in elevation and viewed from a position approximately 180° from the elevational view position of FIG. 2; and

FIG. 4 is a view in elevation of a modified design of the spherical tank for storage vacuum service or similar use shown in FIG. 1 and wherein the median horizontal rib encircles the entire spherical member, the remaining portions thereof being substantially the same in appearance as shown in FIGS. 1, 2 and 3.

I claim:

The ornamental design for a spherical tank for storage vacuum service or similar use, as shown and described.
